UNITED STATES PATENT OFFICE.

LEWIS F. GRISWOLD, OF MERIDEN, CONNECTICUT, ASSIGNOR TO THE
CHAS. PARKER COMPANY, OF SAME PLACE.

SHADE-RING CLAMP.

SPECIFICATION forming part of Letters Patent No. 269,783, dated December 26, 1882.

Application filed November 16, 1882. (No model.)

To all whom it may concern:

Be it known that I, LEWIS F. GRISWOLD, a citizen of the United States of America, residing at Meriden, in the county of New Haven 5 and State of Connecticut, have invented certain new and useful Improvements in Shade-Ring Clamps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The object of this invention is to provide novel and improved means for holding lamp-shades to shade-rings or other supports, whereby the brittle material of said shades shall be exempted from all risk of fracture arising from such fastening, and a single set of attaching devices may be used with divers sizes of shades, said devices automatically adjusting themselves thereto. I accomplish this object by providing a shade-ring with movable 20 clamping-plates, which are formed with hooks that catch under the neck of the shade, said plates being fastened to said shade-ring by screws, preferably the same which attach the harp or lamp-support thereto.

25 In the accompanying drawings, Figure 1 represents a side elevation of the shade-ring, shade, and harp of an extension-lamp, my improvement being applied thereto. Fig. 2 represents a vertical section through the same. Fig. 3 represents a plan view of the shade ring and clamps, and Fig. 4 represents a detail view of one of said clamps.

The same letters indicate the same parts in each of the figures.

30 A designates the lamp-support or harp; B, the shade-ring, to which it is attached by bolts *a a*; and C the shade, which is secured to said ring within the annular flange C', that extends down from the outer lower edge of the latter, as usual. All of these parts, as shown, are suited to an ordinary extension-lamp fixture.

Heretofore screws have generally been passed through flange C' and turned into the neck of the shade, (which is ordinarily of porcelain or similar brittle material,) under the en-

larged upper end thereof. This method of attachment is moderately secure; but it inevitably causes the fracture of many shades, and it is not automatically adjustable to suit different sizes. To avoid these defects I employ 55 clamp-plates D D on opposite sides of said shade-ring, each clamp-plate consisting of a horizontal flat body, *d*, having a bifurcated inner end, *d'*, and a downwardly-extending hook, *d''*, which protrudes through an opening, *e*, in 60 the upper flange, C², and lower flange, C', which make up the external wall of the shade-ring. The outer faces of these hooks are preferably adapted by shape and ornamentation to form part of said wall and be flush with 65 the face thereof. The bodies *d* of the clamps rest upon the usual horizontal flange, C³, on the inside of the shade-ring, and on perforated lugs E, which extend still farther inward therefrom. The perforations or openings of said 70 lugs register with the slots which give the bifurcated shape to the inner ends of said clamp-plates. It is obvious that these plates may be readily drawn into contact with any one of divers sizes of shade, the hooks *d''* 75 catching into the necks thereof, so as to answer the purpose of the ordinary fastening-screws, without any of their inconveniences or defects. Bolts are then passed through the perforations 80 in the lugs E, and the slots in the bifurcated inner ends, *d'*, of clamping-plates D, and their nuts are turned home on top of the latter. These bolts are preferably, though not necessarily, the bolts *a a*, which fasten harp A to shade-ring B.

85 These devices are especially serviceable with extension-lamps, but may be used with those of any other kind.

90 Springs may be employed to render the action of the hooks automatic.

I am aware that it is not broadly new to employ clamping-plates for the attachment of a lamp-shade to its means of suspension or support, nor to supply such plates with springs for rendering them automatic, and therefore I 95 do not claim such constructions, broadly; but

What I do claim is—

1. A shade-ring, in combination with sliding clamping-plates having a hook at one end and bifurcated or slotted at the other, and bolts 100

which fasten the same together, substantially as set forth.

2. A shade-ring provided with perforated lugs and side openings, in combination with bifurcated clamping plates having hooks for grasping the neck of a lamp-shade, a harp or lamp-support, and bolts which serve to attach said harp and said clamps to said shade-ring, substantially as set forth.

In testimony whereof I affix my signature in presence of two witnesses.

LEWIS F. GRISWOLD.
